UNITED STATES PATENT OFFICE.

JAMES LINDSAY, OF NEW YORK, N. Y.

CARPET-STRETCHER.

SPECIFICATION forming part of Letters Patent No. 289,007, dated November 27, 1883.

Application filed October 15, 1883. (No model.)

To all whom it may concern:

Be it known that I, JAMES LINDSAY, of the city, county, and State of New York, have invented an Improvement in Carpet-Stretchers, 5 of which the following is a specification.

The object of this invention is to provide a carpet-stretching device which can be cheaply manufactured, being very readily and conveniently applied to use, and which will insure an exceedingly firm grip upon the carpet during the operation of stretching the same.

My invention comprises a novel combination of parts whereby this object is effectually secured.

Figure 1 is a view showing the apparatus in the position preliminary to grasping or gripping the carpet preparatory to stretching the same. Fig. 2 is a similar view, showing the 20 position of the parts while gripping the carpet in the operation of stretching. Fig. 3 is an end view of the apparatus. Fig. 4 is a plan or top view thereof.

A and B are two jaws, formed, respectively, 25 upon the adjacent extremities of the levers C and D, which are pivoted together, as shown at *a*. The uppermost of these levers has in its rearmost arm the longitudinal horizontal slot *b*. The link E is pivoted at its lower end to 30 the extremity of the rearmost arm of the lower lever, D, by means of a pivot, *d*, the upper end of the said link passing astride of the rearmost arm of the upper lever, C, with a suitably strong pin, *c*, passing through from 35 side to side along and through the slot *b*. The ends of the pin *c* are projected laterally to a distance sufficient to have pivoted upon them the inner end of a draft-link, *f*, the pin being retained in position by being headed over at its extremities. The link E is so arranged that when pushed forward toward the 40 jaws its upper end will be depressed, so that the pin *c*, working on the lower side of the slot *b*, will depress the rearmost arm of the upper lever, and consequently raise the upper one of the jaws. This movement being reversed when the said link E is drawn backward, inasmuch as the link when thus drawn backward moves toward a vertical position, 45 the pin *c* is caused to act on the upper side of the slot *b* in something after the manner of an inclined plane, thereby exerting very 50 great force or power in moving the two jaws

one toward the other, thereby enabling the two jaws to grip the carpet between them with 55 very great security and tenacity.

G is a short pointed pike or staff, which is provided with a hook, *g*.

In applying the apparatus to use, the requisite portion of the carpet is placed between 60 the jaws, and the latter then tightened upon the carpet, as hereinbefore explained. This done, the hook *g* of the pike G is hooked into the draft-link *f* and the point of the pike is thrust into the floor, so that by drawing backward upon the long arm or end thereof the requisite backward movement of the link to grip the jaws upon the carpet is secured; which done, the further backward movement 65 of the long arm of the pike causes the latter 70 to act as a lever to draw the carpet tight by the backward action of the device gripping and holding the same. When the carpet is strained to the requisite degree, the pike is held stationary and the carpet tacked in the 75 usual manner, whereupon a new grip upon another portion of the carpet may be taken as the work proceeds.

It is to be observed that the two levers are to be constructed with suitably coincident lugs, 80 through which the pivot *a* is passed to connect the same, as hereinbefore explained, and that the link E may be either in one piece, provided with suitable lugs to pass astride of the adjacent rearmost ends of the two levers, or it may 85 consist of two parallel portions—one upon each side of the levers—and with the ends pivoted by the pivot *d* to the rear end of lever D, the ends of the pivot *d* being headed over, the upper ends of said pieces being attached to the 90 rear end of the lever C by the pin *c*, passing through the slot *b*, the extremities of said pin being headed over to retain the said ends of the pieces in position.

What I claim as my invention is—
95
The carpet-stretching device composed of the lever C, having the jaw A at one end and a slot, *b*, at the other, the lever D, having the jaw B at one end and the pivot *d* at the other, the link E, pin *c*, and the draft-link *f*, all substantially as and for the purpose herein set forth.

JAMES LINDSAY.
